Attorney.

UNITED STATES PATENT OFFICE

1,982,078

THERMOSTATIC CONTROL

John A. Spencer, Newtonville, Mass., assignor
to General Plate Company, Attleboro, Mass., a
corporation of Massachusetts

Application June 15, 1931, Serial No. 544,454

8 Claims. (Cl. 169—37)

This invention relates to thermostatic controls, and with regard to certain more specific features to a thermostatically operated fluid distributor head or valve.

Among the several objects of the invention may be noted the provision of a thermostatic control of general utility, but which is particularly employed as a temperature-controlled fluid distributor head or valve which is adapted positively to act to release a fluid flow substantially instantaneously, and which is not subject to great variation in operating characteristics, such as critical temperatures, or to deterioration; the provision of a valve or head of the class described which is not permanently impaired, so as to require replacement of parts, with each operation thereof; the provision of a valve or head of the class described which is adapted to distribute fluid over a relatively wide area; the provision of a valve or head which will not close or clog with fluid pressure variations after once it has been opened, except through intentional manipulation; and the provision of an article of the class described which is simple and economical in construction and reliable in operation. Other objects will be in part obvious and in part pointed out hereinafter.

The invention accordingly comprises the elements and combination of elements, features of construction, and arrangements of parts, which will be exemplified in the structure hereinafter described, and the scope of the application of which will be indicated in the following claims.

In the accompanying drawing in which is illustrated one of various possible embodiments of the invention,

Fig. 1 is a vertical section of a valve or head embodying the invention;

Fig. 2 is a top plan view of the valve of Fig. 1;

Fig. 3 is a vertical section similar to Fig. 1, showing an advanced operating position of the valve of Fig. 1; and,

Fig. 4 is a vertical section similar to Figs. 1 and 3 showing a more advanced operating position of the valve of Fig. 1.

Similar reference characters indicate corresponding parts throughout the several views of the drawing.

Attempts to operate fluid distributor valves or heads such as sprinkler heads and the like for fire protection by means of a thermostatic element have heretofore been unsuccessful in that their operation has not been sufficiently quick, positive or reliable. One present type of sprinkler head, employing a fusible link or plug to obtain a me-

dium sensitive to a critical temperature, has the disadvantage that such a link cannot be made to fuse at a temperature as low as is desirable and still retain reasonable mechanical strength. Further, such links often change their fusing points with age. Furthermore, each time the valve is operated, a replacement with an entirely new fusible element is necessitated.

The present invention overcomes the difficulties formerly encountered with thermostatic elements as mediums for obtaining action at a critical temperature and provides a thermostatically operated fluid distributor valve which is positive acting, reliable, and which does not change its critical temperature with age. Moreover, by using the present invention a sprinkler may be provided in which a wide range of critical temperatures may be obtained by using different thermostatic elements, and lower critical temperature may be reached than has heretofore been possible with the fuse link. Also, no element is required to be replaced with a corresponding new element after each operation of the valve, as is the case with fusible links or plugs.

Referring now more particularly to Fig. 1 there is shown at numeral 1 a thermostatically operated valve adapted to be used as a sprinkler head, in cold, closed position, mounted on a pipe 3 which is adapted to convey fluid under pressure, such as water. The sprinkler 1 comprises a base portion 5 which is threaded on the pipe 3 and from which leaf springs 7 extend upwardly. The tops of the springs 7 are bent over as shown in Figs. 1 and 2 to engage a washer 9. A valve stem 11 passes through the central opening of the washer 9, and a valve head 13 on the stem 11 is adapted to seat in a valve seat 15 formed in the pipe 3, to positively cut off communication between the inside and outside of the pipe 3.

The valve head 13 is positively held in the seat 15, against the pressure of the fluid in the pipe 3, indirectly by means of the springs 7. The springs 7 accomplish this holding by reacting downwardly on the washer 9, which in turn presses against portions 17 of a thermostatic disc 19, portions 21 of which press axially against a shoulder 23 formed on the stem 11. The element 19 thus acts as a stop and the springs 7 are adapted to maintain the valve head 13 in its seat 15 by a substantially perpendicular pressure. The thermostatic disc 19 is free at its outer edges 25. The pressure on the edges 17 and 21 is a compression perpendicular to the plane of the disc applied at the center thereof and thus is so placed that it does not affect the snap-acting 110

properties of the disc 19. Other means may be used whereby the element 19 is adapted to stop the valve stem. It is seen from the drawing that the stem 11 passes through an opening 27 in the disc 19.

The thermostatic disc 19 is preferably of the general type illustrated in my copending application filed June 26, 1930, serial No. 463,961 now Patent No. 1,895,590, granted January 31, 1933. Briefly, the thermostat comprises a disc of thermostatic metal such as is usually termed "bimetallic" or "composite metallic", and is preferably, radially corrugated as shown at numeral 29 and as shown in Fig. 1 in the "cold" position, the radially corrugated portion 29 has an originally formed concavity in one direction.

A thermostat of the type illustrated has the property, upon its being brought to a certain temperature, of reversing its direction of concavity. In other words, if the disc be originally considered concave, it becomes convex, or vice versa. The explanation of this phenomenon, is disclosed in my aforementioned Patent No. 1,895,590.

The corrugated disc 19 has the peculiar property that when it snaps, the opening 27 changes in shape and by properly dimensioning said opening, as shown in Figs. 1 and 4, it is conical in a "cold" position of the disc, and substantially cylindrical in the "hot" position, as shown in Fig. 3. The smallest diameter, occurring in the "cold" position, is less than the uniform diameter of the cylinder formed by the opening 27 when the disc is in the "hot" position. When the disc 19 snaps to its "hot" position, the change in size and shape of the opening 27 is sufficient to allow the stem 11 to freely pass through the opening 27. It is noted that the portion 31, which is depressed below the rest of the stem 11, forms the shoulder 23, and that when normally in its "cold" position as shown in Fig. 1, the portions 21 of the disc 19 grip the depressed portion 31.

The operation of the invention as installed in a water, fire protection system is as follows.

The sprinkler head 1 is installed with the pipe 3, which for example, carries therein a relatively high water pressure. The head is assembled as shown in Fig. 1 and seals the pipe 3.

If now the temperature of the disc 19 is raised above its critical temperature it will snap to its "hot" position as shown in Fig. 3. This snapping, however, as hereinbefore described, changes the shape of the hole 27 and the portions 21 are snapped out of holding contact with the shoulder 23 on the stem 11. It is to be noted here that a top portion 33 on the stem 11 has a diameter slightly larger than the main portion of the stem and thus larger than the outer diameter of the shoulder 23 but not quite as large as the uniform diameter of the opening 27. In this way as the disc 19 snaps to its "hot" position the portion 33 centers the stem 11 in the center of the opening 27, positively preventing any of the portions or edges 21 from catching on the shoulder 23.

With the stem thus freed the water pressure acting on the valve head 13 forces it from the seat 15 and thereby forces the stem 11 up through the opening 27, the stem as hereinbefore described being adapted to freely pass through the now cylindrical opening 27. The force of the water escaping raises the valve stem to the top of its motion and holds it there, the valve head and disc 19 forming a distributor for the water.

The cold water, however, escaping from the pipe 3 cools the disc 19 below its critical tempera-

ture and it snaps again to its "cold" position, as shown in Fig. 4. At this stage, it again grips stem 11 with the edges 21 and inasmuch as the springs 7 limit the movement of the element 19, the valve head 13 is positively held above the seat 15. In this position the cold disc 19 and valve head 13 form an effective directing surface for the water. 80

It is noted that when assembled to seal the pipe 3, as shown in Fig. 1, the force exerted on the disc 19 is substantially perpendicular to the plane of the disc and that in snapping to its "hot" position the pressure at the portions 21 and 17 will not interfere with the operation of the disc and hence varying water pressures in the pipe 3 will have substantially no effect on the critical temperature 90 of the disc.

An advantage of the invention is that a snap-acting thermostat has been adapted to a sprinkler head and that the control and action obtained is positive and reliable. An advantage of the thermostatic element thus used in sprinkler heads is that such discs may be provided which will effectively operate at a much lower temperature than the old type of fuse link could be used for. Further inasmuch as the critical temperature of the element 19 does not change with age sprinkler heads installed employing my invention will not require inspection. 95

The assembly may be returned from the Fig. 4 to the Fig. 1 position, when, for example, it is 130 desired to stop the flow of water, simply by manually forcing the thermostatic disc, while cold, to its "hot" position, seating the valve, and allowing the disc to return, under its own force, to its "cold" position. Accordingly no element 110 is required to be replaced, and the valve is again in operable position.

The pipe 3 may comprise a nozzle on which the springs 7 and seat 15 are formed in the factory and may thus be sold as a unit to be installed in 115 pipes of the system.

In view of the above, it will be seen that the several objects of the invention are achieved and other advantageous results attained.

As many changes could be made in carrying 120 out the above constructions without departing from the scope of the invention, it is intended that all matter contained in the above description or shown in the accompanying drawing shall be interpreted as illustrative and not in a 125 limiting sense.

I claim:

1. A fluid distributing valve constructed and arranged to operate at a predetermined temperature to deliver fluid, said valve including a 130 thermostatic element having a hole therethrough, and a stem on said valve passing through said hole, the dimensional characteristics of said hole changing with the temperature-determined alternative positions of said thermostatic element, alternately to restrain and permit free movement of said valve stem.

2. A fluid distributing valve constructed and arranged to operate at a predetermined temperature to deliver fluid, said valve being normally 140 maintained in a fluid retaining condition by a snap acting thermostatic element, said element having a hole therethrough, and a stem on said valve passing through said hole, the dimensional characteristics of said hole changing with the 145 alternative positions of said snap acting thermostatic element and said valve stem having means for preventing said valve stem from movement through said hole when said element is in one position and arranged to allow said valve stem 150

to freely move through said hole when said element is in its alternative position.

of said element, it disengages the stem to permit free opening of said valve.

3. A valve for distributing fluid under pressure having a valve stem, comprising a thermostatic disc having a hole therein through which said stem is passed, the shape of said hole being such that a portion of said element engages a shoulder on said stem when said element is in one of its alternative positions and said valve stem is in its closing position, and resilient means adapted to press against said element to hold said valve stem in its closing position against said fluid under pressure, and the shape of said hole being changed when said element snaps to its alternative position, the then resulting shape being adapted to allow free passage of said stem through said hole, whereby said valve is forced open by said fluid under pressure. 80

4. A valve for distributing fluid under pressure having a valve stem, comprising a thermostatic disc having a hole therein, through which said stem is passed, the shape of said hole being such that a portion of said element engages a shoulder on said stem when said element is in one of its alternative positions and said valve stem is in its closing position, and resilient means adapted to press against said element to hold said valve stem in its closing position against said fluid under pressure, and the shape of said hole being 85

changed when said element snaps to its alternative position, the then resulting shape being adapted to allow free passage of said stem through said hole, whereby said valve is forced open by said fluid under pressure, and means 90

formed on said stem adapted to center said stem in said opening when said element snaps to its 95

last-named position.

5. An assembly for delivering fluid under pre- 100

determined temperature conditions, including a snap acting thermostatic element having a hole 105

therein, and a valve having a stem, said stem passing through said hole, said element having 110

alternative positions determined by the ambient temperature, said thermostatic element being 115

constructed such that, in one of the positions of 120

said element, it engages the stem to prevent opening of said valve, and, in the alternative position

of said element, it disengages the stem to permit free opening of said valve.

6. A thermostatic control comprising a snap- 125

acting, radially corrugated composite metallic disc, said disc having a hole in the center thereof, 80

said hole changing shape as the disc snaps from 85

position to position, and a controlled element fitting in said hole, said controlled element being 90

so shaped that it is locked against movement in 95

at least one direction relative to said disc by said 100

disc in one position of said disc but is permitted 105

freely to move relative to said disc when said disc is in another position.

7. A thermostatic control comprising a radially 110

corrugated composite metallic disc, said disc hav- 115

ing two positions of stability and moving there- 120

between, in response to temperature changes, with a snap action, said disc having a hole at the 125

center thereof, said hole having a lesser diameter 130

in one position of stability of the disc than in the 135

other position of stability, and a controlled ele- 140

ment fitting in said hole, said controlled element 145

being of such diameter that it is locked by said 150

disc against movement in at least one direction 155

relative thereto when said hole is in its said con- 160

dition of lesser diameter, but is permitted freely 165

to move relative to said disc when said hole is in 170

its condition of greater diameter.

8. A thermostatic control comprising a radially 175

corrugated composite metallic disc, said disc hav- 180

ing two positions of stability and moving there- 185

between, in response to temperature changes, with 190

a snap action, said disc having a hole at the center 195

thereof, said hole being conical when said disc is 200

in one of its said positions of stability and sub- 205

stantially cylindrical when said disc is in its other 210

position of stability, the diameter of said hole 215

when cylindrical being greater than the minimum 220

diameter of said hole when conical, and a con- 225

trolled element fitting in said hole, said controlled 230

element being of such diameter that it is locked 235

by said disc against motion in at least one direc- 240

tion relative thereto when said hole is in its said 245

conical position, but is permitted freely to move 250

relative to said disc when said hole is in its said 255

cylindrical position.

JOHN A. SPENCER.
